No. 12,878

Apr. 11, 1882

UNITED STATES PATENT OFFICE.

CANDACE WHEELER, OF NEW YORK, N. Y., ASSIGNOR TO WARREN, FULLER & CO., OF SAME PLACE.

DESIGN FOR WALL-PAPER.

SPECIFICATION forming part of Design No. 12,878, dated April 11, 1882.

Application filed February 13, 1882. Term of patent 3½ years.

To all whom it may concern:

Be it known that I, CANDACE WHEELER, a citizen of the United States, residing at the city of New York, in the county and State of New York, have invented and produced a new and original Design for Wall-Paper, of which the following specification is a clear description, reference being had to the accompanying drawing, forming part thereof.

10 The said drawing represents an elevation of a section of my design for wall-paper. The section of ornamental papering here shown is divided into four distinct fields of ornament—viz., A, B, D, E—by means of the transverse or horizontal bands *a a*, *c*, *F F*, *C*, *C'*, and *C²*. The transverse bands *a a*, *c*, and *F F* are narrow bands or belts enriched with foliated figures. The bands *a a* are two in number, placed respectively at the top and bottom of the base 15 field A. The band *c* is placed a little below the center of the whole section under treatment, and the bands *F F* are two in number, and placed respectively above and below the top or cornice field of ornament E. Each of 20 these transverse bands is quite narrow—say about one or two inches wide, more or less—and it is enriched with foliated ornaments or leaves. The band *C* is placed just below the band *c*, and the bands *C'* and *C²* are respectively placed below and above the two upper bands *F F* and in contact therewith. The said bands *C*, *C'*, and *C²* are each of them about twice the width of the bands *a a*, *c*, and *F F*, and each of them is ornamented with a tessellated 25 ornament. The base field A is equal to about one-eighth or one-tenth of the whole altitude of the section under treatment, and is enriched 30

with geometrical figures. The next higher field of ornament, B, is equal in height to about one-quarter of the height of the section under 40 treatment, and is enriched with foliated vegetation and insectivorous figures. The next higher field of ornament, D, occupies about one-third of the height (more or less) of the section under treatment, and is enriched by means of intersecting lines, forming small geometrical figures, like lace-work, and also by insectivorous figures scattered irregularly over the surface of a cloud-like and florally-decorated background. The cornice field E is quite narrow 50 compared with the fields B and C, and it is ornamented by circular figures somewhat in the usual form of archery targets, and also with foliation and with representations of insectivorous life. These figures and ornaments 55 may be printed or painted on the paper in any desired colors or combination of colors and on any desired color of background.

Having described my invention or design, I 60

claim—

The ornamental design for wall-paper or paper-hangings, consisting of the transverse or horizontal foliated bands *a a*, *c*, and *F F* and the transverse or horizontal tessellated bands or belts *C*, *C'*, and *C²*, with their intermediate 65 panelings or fields of ornament, A, B, D, E, the said fields of ornament being enriched with geometrical figures, foliation, and insectivorous designs, substantially as described and set forth.

CANDACE WHEELER.
